UNITED STATES PATENT OFFICE.

ROBERT HAMILTON LUTZ, OF NIAGARA FALLS, ONTARIO, CANADA.

DIPPER ATTACHMENT FOR STEAM SHOVELS AND THE LIKE.

1,410,201.

Specification of Letters Patent. Patented Mar. 21, 1922.

Application filed April 10, 1920. Serial No. 372,903.

To all whom it may concern:

Be it known that I, ROBERT HAMILTON LUTZ, of the city of Niagara Falls, in the county of Welland, Province of Ontario, 5 Dominion of Canada, have invented certain new and useful Improvements in Dipper Attachments for Steam Shovels and the like, of which the following is the specification.

10 My invention relates to improvements in dipper attachments for steam shovels, and the like, and the object of the invention is to devise a means of tilting the dipper from the position occupied while digging, so that 15 large stones or other material which are too large to pass downwardly through the dipper may be dumped over the top edge thereof; a further object is to provide means for locking the dipper in the digging position when desired.

My invention consists of a steam shovel having the usual main beam carrying the dipper arm and operating mechanism therefor, a dipper hingedly connected at the 25 lower end thereof to the dipper arm, a cross-head bearing in suitable guides carried by the dipper arm, a connecting rod journalled in the crosshead at one end and at the other end in brackets carried at the upper end of 30 the dipper, a ram secured to the crosshead at the end remote from the aforesaid connecting rod, means for reciprocating the ram and means for locking the crosshead in its extreme inward position all as more particularly described and illustrated in the 35 accompanying drawings in which;—

Fig. 1 is a general side elevation of my invention applied to the dipper arm of a steam shovel, the dipper being shown in 40 the tilted position in dotted lines.

Fig. 2 is a plan view of the tilting mechanism. (The crosshead being shown in the extended or tilting position in dotted lines.)

Fig. 3 is a side elevation of same with a 45 portion shown in section on the line 3, 3 of Fig. 2.

Fig. 4 is a section on the line 4, 4 of Fig. 2.

Fig. 5 is a section on the line 5, 5 of 50 Fig. 2.

Fig. 6 is a plan view of a modification of my invention.

Fig. 7 is an elevation thereof with a portion broken away to show a section on the 55 line 7, 7 of Fig. 6.

Fig. 8 is a side elevation showing the motor for operating the pinion driving the dipper arm and also a drum upon which the electric wires are wound, these being carried upon the main beam which is shown in 60 section.

Like characters of reference indicate corresponding parts in the different views.

1 is the main beam connected to the carriage 2 in the usual manner by a hinge 3.

4 is the dipper arm constructed of two I-beams and is mounted in the main beam in the usual manner and operated by the rack and pinion 5 and 6. The pinion 6 is mounted on the shipper shaft 6¹ and is operated by a motor 7.

8 is the dipper which is hinged to the dipper arm by the hinge connection 9. 10 is the bottom door of the dipper hingedly connected thereto.

75

11 is a supporting yoke pivotally carried by the dipper and 12 is a pulley connected thereto. 13 is the hoisting chain which is secured to the sheaf 14 of the pulley 12, passes over the pulleys 15 and 16 carried by the main beam, the pulley 17 carried by the carriage and is finally wound on the drum 18 which is operated from the main driving motor (not shown).

19 is a crosshead sliding in guides 20 and 21 secured to the upper face of the dipper arm by the bolts 22 and separated by the spacer 23.

24 is a connecting rod journalled at one end to the top of the dipper by means of the 90 yoke-end 25, the brackets 26 and the pin 27 and journalled at the other end to the cross-head by means of the yoke-end 28 and the pin 29.

30 is a ram supported in brackets 31 secured to the upper face of the dipper arm by the bolts 32. The ram is provided with the worm 33 and is secured to the crosshead by the strap 34 and the bolts 35.

36 is an electric motor mounted on the 100 dipper arm and 37 is a shaft driven thereby and carrying the pinion 38. 39 is a wheel having an axial orifice therethrough and is revolvably mounted on the ram 30. The worm 33 on the ram engages an internal 105 worm thread 40 on the wheel 39. The wheel 39 has external spur teeth 41 which mesh with the spur pinion 38. 42 and 43 are annular thrust plates freely mounted on the ram at each side of the wheel 39.

95

110

44 are the electric wires to the motor 36. The shipper shaft 6¹ carries a drum 6² of the same diameter as the pinion 6 for a purpose as will appear hereinafter.

5 45 is a steam cylinder having the piston 46 which is attached to the crosshead 19. 47 are brackets supporting the steam cylinder and secured to the upper face of the dipper arm by the bolts 48. 49 is a flexible 10 steam pipe leading to the cylinder 45.

15 50 are Z-shaped locking pins each having the upwardly extending arm 51 and the depending arm 52. 53 is a shaft extending transversely of the dipper arm and having 15 the locking pins 50 freely mounted on its ends.

The crosshead guides 20 and 21 have orifices 54 and 55 extending therethrough and into which the arm 51 of the locking pin is 20 adapted to enter for a purpose as will appear hereinafter.

25 56 is a cord attached to the lower end of the depending arm 52 and extending to the control platform of the shovel. 57 is a coil spring having one end fixed to the dipper arm and the other end to the lower end of the depending arm 52.

30 58 is a piece of rock in the mouth of the dipper which is too large to pass completely into the dipper. 59 is a portion of a railway truck into which the shovel is dumping.

The operation of my invention is as follows:

35 When the dipper is in the digging position the crosshead is at the extreme inner end of its travel and is held in this position, since the ram 30 cannot move until the motor 36 is operated. This position of the 40 dipper is similar to that of the ordinary type and in it the dipper is almost perpendicular to the dipper arm.

45 My dipper is dumped ordinarily in exactly the same manner as in the standard type, the contents of the dipper simply falling out through the bottom door 10.

50 It frequently happens however that large pieces of rock are carried up which cannot pass through the dipper. In this case they 55 can be readily dumped from my dipper by tilting same into the position shown in dotted lines of Fig. 1.

This is accomplished as follows:—
The motor 36 is operated which rotates the shaft 37 and pinion 38. This in turn rotates the wheel 39 which through its internal worm 40 and the worm 33 on the ram reciprocates the latter thus moving the crosshead 19 outwardly and through the connecting rod 24 tilting the dipper. The dipper is returned to the digging position by reversing the motor 36.

The thrust of the wheel 39 is taken by the thrust plates 42 and 43.

55 It will be readily seen that the dipper

is, at all times, locked unless the motor is operating.

The operation of the main beam 1 follows standard practice and will not therefore be described.

In order that the slack produced in the wires 44 due to the operation of the dipper arm will be taken care of, I provide a drum 6² fixed on the shipper shaft 6¹, of the same diameter as the pinion 6 and about which these wires are wound. As the dipper arm is moved in either direction by the pinion 6 the drum 6² rotating therewith either winds up or unwinds the wires 44.

In Figs. 6 and 7 a modification of my invention is illustrated in which the crosshead is operated by a steam cylinder and ram. A flexible steam pipe 49 conveys the steam to the cylinder 45 and the piston 46 reciprocates the crosshead.

In this form, since the dipper is not automatically locked in any position as is the case with the worm device previously described, it is necessary to provide some means of locking it in the digging position.

This is accomplished as follows:—

Locking pins 50 are carried at each side of the dipper arm and are pivotally connected thereto at 53. The crosshead guides 20 and 21 are provided with registering orifices 54 and 55 into which the arm 51 of the locking pin is adapted to extend. The orifices are so disposed that the crosshead uncovers them just as it reaches the extreme inner end of its travel. At this point the 100 dipper is in the digging position.

The coil spring 57 normally holds the arms 51 within the orifices. 56 is a cord which extends to the control platform of the shovel and by pulling it the craneman can withdraw the locking pins from the orifices as desired.

It will be seen that, when the crosshead is at the inner point of its travel and the arms 51 are extending through the orifices 54 and 55 the crosshead is locked in this position, which in turn locks the dipper in the digging position.

Hitherto the dipper has been fixedly connected to the dipper arm and there has been no provision for altering the inclination of the dipper with respect to the dipper arm.

In this construction the dumping is done entirely through the bottom and all material must pass completely through the dipper. This involves the necessity of having all stone shot sufficiently small to pass through the dipper as there is no provision made for dislodging pieces picked up which are 120 too large to pass through.

This naturally involves greater expense in blasting and also considerable time is wasted in picking up large pieces which cannot be dumped.

By the use of my invention however these difficulties are entirely overcome and it will therefore be seen that I have devised improvements in dipper attachments which 5 will very greatly increase the economy and efficiency of steam shovels and the like.

Many modifications may be made in my invention without departing from the spirit of the same or the scope of the claims and 10 the forms shown are to be taken as illustrative and not in a limiting sense.

For instance while I have shown the pinion 38 as meshing direct with the gear wheel 39 I might insert intermediate gears between these two to control the drive. 15

Also various methods of taking care of the slack in the electric wires to the motor might be used, such as a trolley pole and wheel over which the wires would pass. 20

What I claim as my invention is:

1. In a steam shovel, a dipper arm, a dipper hingedly connected to one end thereof, a crosshead mounted in guides carried by the dipper arm, a connecting rod journalled at 25 one end to the dipper and at the other end to the crosshead, a ram supported in brackets carried by the dipper arm and having one end co-acting with the crosshead, the ram having an external thread formed thereon, a wheel mounted on the ram having an internal thread engaging the thread on the ram, thrust bearings at either side of the wheel and means for rotating the wheel. 30

2. In a steam shovel, a dipper arm, a dipper hingedly connected to one end thereof, a crosshead mounted in guides carried by the dipper arm, a connecting rod journalled at 35 one end to the dipper and at the other end to the crosshead, a ram supported in brackets carried by the dipper arm and having one end co-acting with the crosshead, the ram having an external worm formed thereon, a wheel mounted on the ram having an internal worm thread engaging the worm on the ram, thrust bearings at either side of the wheel and means for rotating the wheel. 40

3. In a steam shovel, a dipper arm, a dipper hingedly connected to one end thereof, a crosshead mounted in guides carried by 45

the dipper arm, a connecting rod journalled at one end to the dipper and at the other end to the crosshead, a longitudinally disposed ram supported in brackets carried by the dipper arm and having one end secured to the crosshead, the ram having an external 50 thread formed thereon, a wheel having an internal worm thread, external spur teeth upon its peripheral face, the wheel mounted on the ram and the internal thread thereof co-acting with the worm on the ram, a motor, a shaft rotated thereby, a spur pinion fixedly carried by the shaft and co-acting with the external spur teeth on the wheel, and thrust 55 bearings at either side of the wheel.

4. In a steam shovel, a dipper arm, a dipper hingedly connected to one end thereof, a crosshead mounted in longitudinally disposed guides carried by the dipper arm, a connecting rod journalled at one end to the dipper and at the other end to the crosshead, 60 screw means for reciprocating the crosshead and means for locking the crosshead at the innermost point of its travel. 65

5. In a steam shovel, a dipper arm, a dipper hingedly connected thereto, a crosshead mounted in guides carried by the dipper arm, a connecting rod journalled at one end to the dipper and at the other end to the crosshead, means for reciprocating the crosshead, a locking pin carried by the dipper arm and means for engaging said pin with the crosshead for locking it at the rearmost 70 point of its travel. 75

6. In a steam shovel, a dipper arm, a dipper hingedly connected thereto, a crosshead mounted in guides carried by the dipper arm, a connecting rod journalled at one end to the dipper and at the other end to the crosshead, means for reciprocating the crosshead, locking pins carried by the dipper arm, means for projecting said pins into the path of the crosshead to engage its front end when the crosshead is at the rearmost point 80 of its travel. 85
